UNITED STATES PATENT OFFICE.

JOHN C. F. SCHAFER, OF MOUNT PULASKI, ILLINOIS.

DAMPER.

1,296,857.

Specification of Letters Patent. Patented Mar. 11, 1919.

Application filed October 4, 1915. Serial No. 54,009.

To all whom it may concern:

Be it known that I, JOHN C. F. SCHAFER, a citizen of the United States, residing at Mount Pulaski, in the county of Logan and 5 State of Illinois, have invented a new and useful Improvement in Dampers, of which the following is a specification.

The invention relates to dampers for stove pipes. The purposes of the invention are to 10 provide in conjunction with the pipe and the damper plate, more effective and convenient means than have hitherto been employed to perforate the pipe with which the damper plate is used; to provide on the 15 damper plate, in conjunction with the pipe, means whereby the perforations in the wall of the pipe may be made at a uniform distance from one terminal edge of the wall of the pipe, gaged by instrumentalities 20 constituting part of the damper plate itself, and to provide improved details of construction, to be hereinafter described and finally recited in the claims.

The invention is illustrated in the annexed 25 drawing in which the same reference numbers designate the same parts in both views.

Figure 1 is a top plan of the damper in closed position in a stove pipe, and Fig. 2 shows, in side elevation, a damper plate on 30 a stove pipe in position for perforating the pipe.

The circular damper plate 1 is preferably of cast iron, but obviously may be pressed from sheet metal. The plate 1 has a smoke 35 opening 12; a transverse radial slit 2; a notch 3 in line with the slit 2; an internally screw threaded boss 4 at right angles to the plate and adapted to accommodate the screw-threaded part 7 of the damper-rod 6; a forked boss 5 in range with the boss 4; a circular strengthening rim 10; concavo-convex members 9 in pairs in range with each other, the members of the respective pairs being curved oppositely to accommodate the 45 damper-rod 6, and the members of one pair having notches 19 to accommodate radial pins 13 on the rod 6; and openings 20 between the pairs of members 9 and adapted to be traversed by the pins 13 when the rod 50 6 is rotated in the members 9.

The boss 4 serves as a screw-support, and the boss 5 serves as an abutment against which the wall of the pipe is held while perforating it.

55 I have shown the screw-support and the

abutment integral with the damper plate; but they may be made separately and attached in any suitable manner to the damper plate.

The damper rod 6 has a handle 14 for manipulating the rod; a collar 17 adapted to slide in the sleeve 15, radial pins 13 adapted to engage in the notches 19 of the members 9; a screw-threaded part 7 adapted to engage the internal screw threads of the boss 65 4; and a tapered terminal 8 adapted to perforate the metal of the pipe 18.

The rod 6 serves as an axle for the damper plate; and in conjunction with the screw-support 4 and the abutment 5, serves to perforate the wall of a pipe held against the abutment while the rod is turned in the screw-support.

A coiled spring 16 surrounds the part of the rod 6 which is in the sleeve 15 and acts 75 on the collar 17 to normally keep the parts in the position shown in Fig. 1. Pushing on the handle 14 will cause withdrawal of the pins 13 from the notches 19 to permit a half-rotation of the rod 6 to disengage the 80 pins 13 from the ends of the concavo-convex members 9 to permit the rod to slide outwardly into such position that the inner pin 13 may traverse the adjacent opening 20, and a second half-rotation of the rod will 85 disengage the inner pin 13 from the inner end of the outer member 9 so that the rod 6 may be completely withdrawn from the members 9.

To perforate the pipe 18 preparatory to placing the damper plate 1 in proper position in the pipe, the plate will be placed on the pipe with the upper edge of the pipe in the notch 3 and the wall of the pipe in the slit 2 and adjacent to the abutment 5; the rod 6 will then be screwed into the screw-support 4 to bring the point 8 in contact with the outer surface of the pipe to press the wall of the pipe against the abutment 5, and the rod will then be rotated to cause 100 the tapered terminal 8 to perforate the wall of the pipe. The plate 1 will then be moved to a diametrically opposite position on the pipe, and a second perforation in line with the first perforation will be made in like 105 manner. The plate 1 supported on the upper edge of the pipe, as shown in Fig. 2, gages accurately the distance of the perforations from the end of the pipe so that both perforations will always be in the same plane 110

at right angles to the axis of the pipe, thereby assuring accurate placing of the plate in the pipe.

I am aware that damper rods adapted to perforate pipes have been used and that damper plates having oppositely curved concavo-convex members adapted to accommodate the damper rod have been used. I therefore, do not broadly claim those features of construction.

What I claim as new and desire to secure by Letters Patent is:

1. A damper adapted for use in a pipe; comprising a discal main structure adapted for use as a damper plate and having rod supporting members, a central opening, a radial slit adapted to accommodate the wall of a stove pipe, and a notch in line with said slit and adapted to accommodate the upper edge of the wall of the pipe, a screw-threaded lug on one side of said slit, an abutment on the opposite side of said slit and in line with the screw-threaded lug, and a pointed damper rod having near its pointed end a screw adapted to engage in the screw-threaded lug to cause the point of the rod to perforate the wall of the pipe upon rotation of the rod.

2. A damper adapted for use in a pipe; comprising a discal base adapted for use as a damper plate and having a central opening, also having a slit adapted to accommodate the wall of a pipe; a screw threaded lug extended outwardly from the base on one side of the slit; an abutment extending outwardly from the base on the opposite side of the slit; rod supporting members diametric to the base and adapted to accommodate a damper rod to support the base in the pipe; and a screw-threaded damper-rod adapted to engage in the screw-threaded lug on the base while in use to perforate the wall of the pipe, also adapted to occupy said rod-supporting members while not in use for perforating the wall of the pipe.

3. In a damper, the combination of a

damper plate, having rod-supporting members and a slit; a screw-support on the damper plate; an abutment on the damper plate and complementary to the screw support; and a pointed screw-rod adapted to serve as the axle of the damper plate and also adapted to engage in the screw-support to cause the rod to perforate the wall of the pipe in contact with the abutment during the rotation of the rod in the screw-support.

4. A damper adapted for use in a pipe, comprising a plate having a slit adapted to accommodate the wall of a pipe, a screw-threaded member on one side of the slit, an abutment on the opposite side of the slit, in line with the screw-threaded member and rod-supporting members transverse to the plate and adapted to accommodate a rod to support the plate in a pipe; and a screw-threaded damper rod adapted to engage in the screw-threaded member of the plate, while in use to perforate the wall of a pipe, also adapted to occupy said rod-supporting members while not in use for perforating the wall of the pipe.

5. In an appliance of the class described, the combination of a pipe, a damper-plate having rod-supporting members, a central opening; a slit, a notch in line with the slit, a screw-support and an abutment in line with the screw-support; and a pointed screw-rod adapted to serve as a support for the damper-plate, also adapted to engage in said screw-support to make a perforation in the wall of a pipe occupying the slit and notch in the damper plate, said perforation being at a distance from the end of the pipe equal to the distance from the apex of said notch to the axis of said screw.

In witness whereof I have hereunto signed my name at Mount Pulaski, Illinois, this 30th day of September, 1915.

JOHN C. F. SCHAFER.
